Specification for Design.

Patented Nov. 12, 1918.

Application filed September 29, 1917. Serial No. 194,097. Term of patent 14 years.

To all whom it may concern:

Be it known that I, EDGAR S. BOTT, a citizen of the United States, residing at 1214 Caledonia street, in the city of La Crosse, county of La Crosse, and State of Wisconsin, have invented a new, original, and ornamental Design for Ankle-Guards for Shoes, of which the following is a specification, reference being made to the accompanying drawing, forming a part thereof.

The figure is an elevation view of the rear portion of a shoe to which the ornamental design has been applied, the shoe being indicated by dotted lines.

I claim:

The original and ornamental design for ankle guards for shoes as shown.

EDGAR S. BOTT.
